United States Patent Office

Des. 209,544
Patented Dec. 12, 1967

209,544

JAR

Bruce L. Roberts, Rossford, Ohio, assignor to Owens-Illinois, Inc., Toledo, Ohio, a corporation of Ohio

Filed July 7, 1966, Ser. No. 2,962

Term of patent 14 years

(Cl. D58—25)

FIG. 1

FIG. 2

FIG. 1 is an elevational view of a jar showing my new design, the side opposite that shown being the same in appearance as the side shown;

FIG. 2 is a top plan view thereof.

I claim:

The ornamental design for a jar, substantially as shown and described.
